UNITED STATES PATENT OFFICE.

FRANK E. MILLER, OF NEW YORK, N. Y.

FIXED SELECTIVE STETHOSCOPE.

1,282,908.

Specification of Letters Patent. Patented Oct. 29, 1918.

Application filed February 14, 1918. Serial No. 217,045.

To all whom it may concern:

Be it known that I, FRANK E. MILLER, a citizen of the United States, and a resident of New York city, county and State of New York, have invented certain new and useful Improvements in Fixed Selective Stethoscopes, set forth in the following specification.

This invention relates to the making of soundings on the human body. The ordinary method of making soundings through the medium of a portable stethoscope is many times extremely trying both to the physician and to the patient, particularly in the case of a patient confined to his bed and in a critical condition, although soundings may be necessary, the making of the same may be fraught with actual danger to the patient, due to exposure and the attendant excitement.

The object of my invention is to provide for the making of soundings upon the body of a patient under conditions of no discomfort to the patient and of convenience to the physician. Although soundings are most frequently employed in connection with the thorax, my invention is by no means limited to such a locality, although in such use it may have the most advantage. In furthering my invention I contemplate the location of a plurality of electrical transmitters positively positioned relatively to the desired parts of the human anatomy to be explored through the medium of a garment to which they are physically attached and which is to be worn by the patient.

I further contemplate suitable circuits, receiving apparatus and selective control means whereby the receiving apparatus may be actuated by any set of one or more of the specially located transmitters.

The above and further objects of my invention will better be understood by reference to the illustrative embodiment set forth in the following specification, in connection with the accompanying drawings, which form a part hereof, in which like characters designate corresponding parts in the several figures. In the drawings Figure 1 is a top plan view of a recumbent patient fitted with my invention; Fig. 2 is a bottom plan view of the structure of Fig. 1; Fig. 3 is a cross section, looking in the direction of the arrows, through line III—III of Fig. 1 and drawn to an enlarged scale; and Fig. 4

is a diagram of illustrative circuit connections.

I employ preferably special electrical transmitters of the type employed in the United States Army aviation helmets, examples of which are indicated by A with various exponents in the drawings. Although I have found this particular type of transmitter highly suitable for my purpose, my invention does not reside in the type or construction of transmitter. I am aware that any common type of electrical transmitter is more or less suitable for my purpose, but it is preferred that the type responsive to sound transmitted through chest vibration rather than air vibration be used.

A garment for enveloping the part of the body to be sounded is formed in the desired size and configuration. This garment may be in the form of a harness of straps such as a suspender waist, but is preferably a garment such as the shirt B, formed of two layers of textile fabric 1 and 2, suitably stitched and provided with buttons 3, as is usual in the formation of such garments. In the practice of my invention for body soundings, as through the medium of the structure illustrated in the drawings, I prefer to arrange the transmitters in sets of two each, one directly in front and one directly in the rear of the locality to be sounded. For example, the transmitters A¹ and A² are shown positioned respectively in the rear and the front of the lower lobe of the right lung, while transmitters A³ and A⁴ are shown respectively directly at the rear and at the front of the lower lobe of the left lung. In a similar manner, the transmitter A⁵ is positioned directly over the stomach opposite to the transmitter A⁶, shown in dotted lines in Fig. 2, in the rear of the stomach. In a similar manner, other sets of transmitters such as A⁷—A⁸, A⁹—A¹⁰, A¹¹—A¹², and A¹³—A¹⁴ are shown with the individual transmitters of each set respectively at the front and the rear of a body locality which it may be desired to have sounded, for example, such localities as the remaining of the five lobes of the lungs and the heart.

A two-wire electrical conducting cord C, suitably electrically connected with the terminals of each transmitter is carried through the garment B between its fabric layers, where it is preferably stayed in position

105

110

through a suitable stitching through a trunk cable D, from which the necessary electrical branches are made, as will appear more in detail in the diagram presently to be described. Each transmitter is likewise stayed in its predetermined position in any suitable manner, as by stitching 4. The cable D is preferably located along the garment in a position corresponding to the patient's side, so as to interfere in the least degree with the comfort of the patient when in a reclining position. The cable D is extended out as a unitary structure from the garment so that it may emerge from the bed-clothes and extend to any desirable distance as, for example, to a room other than that occupied by the patient under observation.

A suitable source of electric energy, such as the battery E, is provided and located preferably at the distance desired away from the patient, usually in the locality of the receiving station at which is located the receiver F and the usual form of telephone transformer G and a selective control switch H. In making up the trunk cable D, one common battery wire 5 throughout the length of the cable is sufficient, the same being provided with appropriate branches 6, 7, 8, 9, 10, 11 and 12, one for each of the sets of transmitters, to one terminal of each of which these branches are connected. The opposite branches of each set of transmitters has a selector wire such as the wires 13, 14, 15, 16, 17, 18 and 19 respectively, which go to complete the cable C and extend to corresponding contacts h^1 , h^3 , h^5 , h^7 , h^9 , h^{11} , h^{13} of the switch H, which contacts h^1 and so forth, are characteristically numbered or lettered to correspond in their indication with the location of the transmitters which they control. From the switch arm 20 a wire 21 leads to the transformer G, which is also connected through the wire 22 with the battery E. Transformer G is connected with the receiver F through the wires 23 and 24, preferably as is customary in the form of a flexible cord. It is contemplated that the receiver F may be in any of the well-known forms of receivers, either ear-phones or a stationary loud-speaking phone.

In using my invention the patient is clad with a garment designed especially to accord with the particular disease or trouble under treatment or observation. This is accomplished without professional technique or any unusual procedure which might excite a patient. The necessary circuit connections

are made and the observer, who may be located in a distant room, can, at will, continuously if necessary, without the knowledge of the patient, make soundings of any locality corresponding to the positioning of the sets of transmitters. It is contemplated that many of the various parts of the apparatus may be duplicated without involving invention, as for instance it is not necessary to limit the reception of soundings to one receiver F, as any desired number of duplications may be made by increasing the number of receivers and switch arms 20, so that simultaneous observations or soundings of different localities may be made by two or more operators. It is also appreciated that this invention is not necessarily limited to the observation of diseased patients and that it has other usefulness, as for example, the testing of the resonating capacity of singers. For example, a patient fitted with a suitable embodiment of the apparatus can be instructed to reproduce the sounds noh, nah and nee, which are calculated to produce a maximum vibration respectively in the upper, middle and lower lobes of the lungs. A trained operator may thus readily gage and determine a student's progress or lack of progress in the control of this vocal resonance.

What I claim is:

1. A stethoscope comprising a body garment; a plurality of transmitters each fixed to said garment in a predetermined locality relatively to a body-organ; a source of electric energy; a receiver; and means for selectively connecting said source and receiver with selected sets of one or more of said transmitters.
2. In combination a body garment; a pair of transmitters anchored to said garment at localities such as that when the garment is applied to a human body said transmitters will occupy opposed front and rear positions; and electric connections connecting said transmitters in parallel.
3. In combination a body garment; a plurality of transmitters anchored at various localities to said body garment; electric connections for each of said transmitters; and a flexible cable electrically connected with said connections and extending away from said garment.

In testimony whereof I have signed my name to this specification, this 25th day of January, 1918.

FRANK E. MILLER.
